COMBINED INTAKE AND EXHAUST MANIFOLD

Arthur F. Milbrath, Milwaukee, Wis.

Original application May 12, 1930, Serial No. 451,540, now Patent No. 1,910,558, dated May 23, 1933. Divided and this application December 17, 1931, Serial No. 581,589

2 Claims. (Cl. 123—123)

This application is a division of my former application, Serial No. 451,540, filed May 12, 1930, for Internal combustion engine, now Patent No. 1,910,558.

5 My invention relates to improvements in combined intake and exhaust manifold assemblies, the object of which is to provide increased efficiency by an improved arrangement, whereby the heat of exhaust gases may be transferred to 10 the combustible mixture in the intake manifold risers, and whereby the number of heat units so transferred may be automatically controlled in inverse proportion to the load and the quantity of fuel used.

15 Another object of my invention is to provide a series of curves in the heated risers and intake manifold of an internal combustion engine, whereby heavy particles of fuel may be caused to impinge upon heated surfaces and more thoroughly vaporized or broken up.

20 My improved manifold also is so designed as to pass exhaust gases completely around the intake manifold and so designed as to avoid dead spots inimical to complete and positive circulation and heat transfer to the fuel gases.

25 In the drawing:

Figure 1 is a plan view of a six cylinder engine embodying my invention, with cylinders cast in pairs, one pair being shown in horizontal 30 section on line 1—1 of Figure 2.

Figure 2 is a vertical section on line 2—2 of Figure 1.

Figure 3 is a section on line 3—3 of Figure 1.

Figure 4 is a section on line 4—4 of Figure 3.

35 Like parts are identified by the same reference characters throughout the several views.

My improved exhaust and intake manifold assembly is shown in the drawing incorporated in a multiple cylinder engine, in which cylinders 10 are cast in pairs, although it will be obvious 40 from the description hereinafter set forth that a similar construction carrying out the purposes and essence of my invention may be incorporated in any internal combustion engine whether the cylinders are cast in pairs or not.

45 As indicated probably most clearly in Figures 1 and 2, each of the cylinders 10 is provided with an exhaust port 11 opening from a side wall 12 of the cylinder block and extending to an exhaust valve 13 opening into cylinder 10, and each of the cylinders is likewise provided with 50 an intake valve 14 controlling the input of gases through a port 15 which likewise opens upon the same face 11 of the cylinder block. Preferably 55 the intake port 15 opens into the cylinder block

upon a different level than the exhaust port 11.

Between the port 15 and the carburetor, not shown, the usual riser 16 and intake manifold 17 complete the conduit through which fuel gases are passed to the cylinder 10, and it is during 60 this passage that the heating and breaking up of heavy particles of fuel gases accomplished by means of my improved manifold construction is carried out. In the six cylinder engine shown in the drawing, the intake manifold 17 comprises a conduit extending along the side of the engine and provided with branches or curved portions flanged for attachment to the cylinder block 12 in the manner conventional in internal combustion engine construction.

But I have provided at 18 a junction box construction which includes in it, as shown most clearly in Figures 3 and 4, a curved conduit 19 connecting the riser 16 with the intake manifold 17, and incorporating with such conduit a 70 jacketed structure for carrying exhaust gases around the conduit 19 and the intake manifold 75 17, as will be hereinafter described.

Each of the junction boxes 18 likewise comprises in a jacket portion 20 a continuation or 80 connecting element between conduits forming an exhaust pipe 21 which interconnect various ports 11 of the cylinders in my multiple cylinder engine. Extending out of the jacket portion 20 of each of the junction boxes is an exhaust pipe 85 22 which receives and delivers to any conventional type of muffler the exhaust gases coming from the cylinders 10.

It will be noted in Figures 3 and 4 that the junction boxes 18 are provided with a separable 90 cap portion 23 joined to the junction box 18 by means of cap screws 24, and apertures 25 between the junction box 18 and its cap 23 provide passages for exhaust gases to pass into jacket portion 26 in the cap 23, thus establishing clearly a 95 heated zone for conduit 19 and the T-shaped junction of conduit 19 with intake manifold 17.

Attention is called to the fact that as shown clearly by Figure 3 that the direct path of exhaust gases in exhaust manifold 21 is partially 100 interrupted by the curved portion of conduit 19 so that there is an interruption in the flow of gases from the exhaust manifold 21 to the exhaust pipe 22 through the junction box 18. Eddy currents thus set up are forced through the apertures 25 into the cap portion 23 so as to ensure complete 105 heating of the intake manifold 17.

The curves of conduit 19 in addition to their performance of the function described in the foregoing paragraph also assist in carrying out 110

one of the principal objects of my invention,—
namely, to cause a more complete vaporization of
fuel particles. The passage of fuel mixture
through the riser 16 and the conduit 19 is rapid
5 and the heavy particles of unvaporized fuel by
their velocity and momentum are caused to im-
pinge on the heated interior surfaces of the S
curves of the conduit. The resultant friction
and the heating of these particles is effective to
10 carry out the vaporization desired, especially
when the process is completed through the
T-joint at the junction of the conduit 19 and the
manifold 17, which is likewise heated by the
jacketed cap 23.

15 Engines to which I have found my invention
best adapted are of the type using heavy fuels
which require more heat transfer in the intake
manifold at slow speeds than at high speeds; and
I have found that structure such as that shown
20 and described herein accomplishes the desired
result probably by reason of the shape and relation
of the parts and partly by reason of the dis-
position of my "junction box" adjacent the
T-joint of the riser 16 with the horizontal mani-
25 fold 17, since I have found that jacketing of an
exhaust pipe around and along the horizontal
manifold results in too great heat transfer.
I have found that in the ordinary operation
30 of an engine equipped with my improved device
the "idling" periods of operation, the rise in tem-
perature of the fuel entering the cylinder, is cor-
rect for such speeds and when the engine is
speeded up the rapid passage of fuel through the
35 junction box reduces the period of exposure to
hot surfaces in the junction box and permits

entry of fuel at lower temperatures as is required
in the use of heavy fuel.

I attribute the success of my invention in part
at least to the combination of curved conduits
and manifold junctions with provision for heat-
ing said curves so that long stretches of conduit
need not be jacketed, although I do not wish to
limit myself to this one theory with respect to its
operation.

I claim:

1. A junction box for an intake and an exhaust
pipe of an internal combustion engine, whereby
the intake pipe passes through the exhaust pipe
and is jacketed thereby, and the intake pipe is
formed in a T-joint adjacent its junction with the
exhaust pipe, said T-joint being provided with a
jacketed cap provided with apertures intercom-
municating with the exhaust pipe, the intake
pipe being disposed to impede passage of exhaust
gases to produce eddy currents directed through
said apertures, whereby to heat the intake pipe
and the T-joint thereof.

2. The combination with a multiple cylinder
internal combustion engine, of an exhaust pipe
extending from one cylinder to another and pro-
vided with an enlarged junction box cavity there-
between, an intake pipe passing through the
junction box cavity and formed in a T-joint adj-
acent thereto, and a cap fitting comprising a
jacket housing for the T-joint with ducts inter-
communicating with the junction box cavity, the
intake pipe being positioned in the junction box
cavity in a position to cause eddy currents of
exhaust gases directed into said ducts.
